UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC-LAMP SOCKET.

1,072,271.

Specification of Letters Patent.

Patented Sept. 2, 1913.

Application filed February 23, 1912. Serial No. 679,311.

To all whom it may concern:

Be it known that I, GEORGE B. THOMAS, a citizen of the United States of America, and residing at Bridgeport, in the county of 5 Fairfield and State of Connecticut, have invented a certain new and useful Improvement in Electric-Lamp Sockets, of which the following is a specification.

My invention relates to electric lamp sockets and particularly to the switch mechanism thereof, the object of my invention being to increase the safety, efficiency and current-carrying capacity of the switch mechanism by providing a device which 15 smothers the arc which tends to form between the parting edges of the switch contacts on the opening of the switch.

In the accompanying drawings, Figure 1 is a side elevation of the body of a standard electric lamp socket in which my invention is embodied in one form; Fig. 2 is a similar view showing the switch mechanism in another position; Fig. 3 is a perspective of the rotary switch contact; Fig. 4 is a plan of the same with my improved insulating device thereon; Fig. 5 is a cross section of the latter on the line 5—5, Fig. 4; and Fig. 6 is an inverted perspective of the same. Fig. 7 is a dropped perspective 30 showing the operating ratchet and rotary switch piece detached with the ratchet plate tilted up to show the ratchet teeth.

The socket illustrated is, in its main features, of the type illustrated in the Hubbell Patent No. 693,799, and comprises insulating buttons A and B spaced apart by standards 10, 11 and 12, and between which the switch mechanism is mounted on a central spindle 13. This mechanism comprises 40 an actuating pawl plate 14 pivoted on the spindle 13 and subjected to the action of a return spring 15, in well known manner. The plate 14 carries as usual a chain rail 16 to which is secured the pull chain 17. 45 The downwardly angled lugs 18 of the plate 14 engage the edges of the radial arms 19, on the rotary switch contact 20, mounted upon the spindle 13 beneath said plate. The stationary switch contact 22 is mounted on 50 one of the inclines of the ratchet-formed boss 21, which projects from the upper face of the button B, while the arms 23 of the rotary switch piece ride over the inclines of the boss 21 as usual.

55 When one of the arms 23 leaves the top of

the incline upon which the stationary contact 22 is mounted, on the break of the switch circuit, there is a tendency to form an arc between the parting edges of the stationary contact 22, and of the rotary switch contact 23. This tendency, in the case of an excessive current passing through the lamp circuit, is quite marked, and introduces an element of danger which is ordinarily provided against by automatic cut-outs of limited current carrying capacity installed in the circuit. These necessarily limit the number of lamps which may be mounted in a single circuit. To eliminate this danger, I now propose to mount upon 70 the rotary contact member an insulator which, upon the opening of the switch, is automatically interposed between the parting edges of the rotary and stationary switch contacts, and forms a barrier between the 75 same, so that not only is any arc which tends to form smothered thereby, but the accidental formation of an arc between the contacts while the switch is in the off position is prevented.

In the particular embodiment of my invention illustrated, which must be regarded as merely exemplary, since there are various ways of accomplishing the same end, I mount upon the upper face of the rotary 85 contact a ring 24 of insulating material which is provided with downwardly projecting shoulders 25, following the incline of the arms 23. Upon the opening of the switch, these shoulders are automatically interposed in the space between the lower end of the contact arm 23 and the upper end of the stationary contact 22, thus completely blocking the space between these contacts, as shown in Fig. 2. To further separate 95 these contacts from each other, I provide the insulating ring with a downwardly projecting peripheral skirt 26 which prevents the formation of an arc around the interposed shoulder 25 between the outer edges 100 of the contacts. The insulating ring 24 with its skirt 26 thus forms a rotary insulating barrier and casing which, in combination with the base B and the hub of the boss 21, completely incloses each of the contact arms 105 23 in the "off" or open position of the switch—completely insulating the same from the stationary contact 22. In order that this insulating ring may lie flush with the upper face of the contact plate so as not to inter- 110

fer with the operation of the actuating plate 14, the contact arms 23 are offset downwardly at a point beyond those portions of the radial arms 19 which form the coöperating ratchets for the downwardly angled pawls of the plate 14, and in this offset the insulating ring is fitted as shown in Fig. 5.

Upon the actuation of the switch, the rotary switch member and insulating ring rise 10 on the inclines of the boss 21, and one of the rotary contact arms 23 passes over the stationary contact 22. As the lower end of the rotary contact arm 23 escapes the upper end of the stationary contact 22, the spring 15 15 forces the rotary contact and insulating ring down upon the succeeding incline of the boss 21. The shoulder 25 and the skirt 26 of the insulating ring during this downward travel of the contact 23 are interposed 20 between the parting edges of the contacts and not only snuff out any arc that might tend to form between the parting edges of the contacts, but serve to incase the rotary contact arm and positively insulate it from 25 the stationary contact.

It is obvious that this device so increases the capacity of the switch that a much heavier current may be broken thereby with safety, and consequently the number of 30 lamps on a given circuit may be materially increased.

I claim as my invention:—

1. A switch mechanism for electric appliances, comprising a series of inclined faces 35 and a stationary contact thereon, in combination with a rotary switch contact having contact arms to pass over said inclined faces and contact, means to intermittently rotate the movable contact, in combination with insulating material interposed between the parting edges of said stationary and rotary contacts upon the opening of the switch, together with a peripheral skirt of insulating material depending around the outer normally exposed edge of said contact arms.

2. A switch mechanism for electric appliances, comprising a series of inclined faces and a stationary contact thereon, in combination with a rotary switch contact having

contact arms to pass over said inclined faces 50 and contact, means to intermittently rotate the movable contact, in combination with a ring of insulating material overlying said contact arms and provided with downwardly inclined shoulders following the incline of 55 said contact arms, whereby said shoulders are interposed between the parting edges of said stationary and rotary contacts upon the opening of the switch, said contact arms being offset at their upper end to permit the 60 insulating ring to lie flush with the upper face of the rotary contact.

3. A switch mechanism comprising stationary insulating base, a stationary switch contact thereon, a rotary contact coöperating with the stationary contact and a rotary insulating body coöperating with the stationary insulating base to completely inclose and insulate the rotary contact from the stationary contact in the off position of the 70 switch.

4. In an electric switch, a rotary switch member comprising a central bearing plate having outwardly extending arms and arcuate downwardly angled contact wings offset 75 at their junction with said outwardly extending arms.

5. In an electric switch, a rotary switch member comprising a central bearing plate, outwardly extending arms forming a ratchet 80 element and arcuate downwardly angled extensions offset from said arms to form contact wings, substantially as described.

6. In an electric switch, a rotary contact member comprising a central bearing portion, peripheral contact wings, in combination with an insulating ring overlying only 85 said contact wings whereby said central bearing portion is left exposed for the purpose specified.

In testimony whereof I have signed my name to this specification, in the presence of two subscribing witnesses.

GEORGE B. THOMAS.
